UNITED STATES PATENT OFFICE.

EDWARD E. CLEMENT, OF WASHINGTON, DISTRICT OF COLUMBIA, ASSIGNOR TO
EDWARD F. COLLADAY, OF WASHINGTON, DISTRICT OF COLUMBIA.

TRAFFIC-CONTROL SYSTEM FOR RADIO BROADCAST DISTRIBUTION.

Application filed April 10, 1925. Serial No. 22,172.

The present invention relates to the art of radio broadcast distribution and has for its object the provision of a system of broadcast distribution to selected subscribers from a central station, particularly the central station of a semiautomatic telephone exchange system, the subscribers being given the benefit of sensitive receiving apparatus with full amplification without the use of 10 vacuum tubes at the subscribers' stations, the necessary tubes being located at the central station with means at the central station for operatively connecting a tube or set of tubes with a subscriber's line and distributing 15 radio broadcast matter therethrough to the subscriber's substation. The system also provides means for affording the subscriber a selection of different programs furnished by his associated central station or by other 20 central stations of the system.

The invention is illustrated in the accompanying drawings in which:

Fig. 1 is a schematic diagram of a semiautomatic telephone exchange system embodying the invention.

Fig. 2 shows a subscriber's substation apparatus, line, and line terminal apparatus or primary control circuits and apparatus.

Fig. 3 shows a link circuit, for linking a 30 calling line with an idle selector switch for selection of a switching mechanism affording access to groups of subscribers or broadcast programs.

Fig. 4 shows a connector trunk and switch 35 for selection of and connection with any one of a group of subscribers' line terminals.

Fig. 5 shows the operator's trunk with secondary selector switch and key set control.

Fig. 6 shows the operator's key set and sending machine.

Fig. 7 shows a subscriber's party line.

Fig. 8 shows a broadcast service link circuit with line tube.

Fig. 9 is a layout plan showing how the several sheets of drawings should be combined to show the entire system.

As the combination of circuits and apparatus constituting the general system here 50 shown and its operation, are shown and described in detail in Patent No. 1,230,996, granted to me June 26, 1917, it will suffice here to describe the general system in outline referring to the schematic diagram Fig. 55 1 for an understanding of the system of se-

lective switching forming an element of the present invention, a detailed description being given of what in the present case is new over the disclosure of the patent above referred to.

In Fig. 1, each element is marked with the title by which in general it will be designated throughout the case, and enough of the reference letters and numerals are shown for purposes of comparison and to gain a 60 general understanding of the relation of the various parts of the circuits shown in the other diagrams. It may be here stated that for convenience all calls for broadcast reception or for telephone connections will be 65 assumed to originate at the left hand end or station, and all connections to progress toward the right, the wanted or called subscriber being assumed as the right hand subscriber in every case. Of course, it will be 70 understood that there is no such limitation in practice, but this assumption simplifies description and illustration. In this figure therefore three subscribers' stations are 75 shown at the left hand end of the sheet, each provided with a telephone set and a broadcast receiving set whose lines terminate on 80 multiple contacts of three primary selector switches, each of which has a pivoted wiper or contact which can be swept over the line 85 contacts to connect with any one of them. Each of these wipers forms one terminal of a selector trunk, the other terminal of which is a similar wiper in the selector switch. The fixed contacts over which these wipers 90 sweep in all the switches are usually referred to as bank contacts, and in mass as "contact banks."

From the bank contacts of the selector 95 switches connector trunks are taken in multiple to the wipers of connector switches. The banks of these connector switches contain only line terminals, just the same as the primary selectors. At the right hand end of Fig. 1 two subscribers' lines are shown, each 100 with four subscribers' stations connected to it in parallel. These are party lines, so shown for the purpose of illustrating the principle of selective ringing. They need not all be party lines however, nor is it necessary that the subscribers shown on the right of Fig. 1 should be different from those shown at the left. On the contrary, every subscriber's line, in order to have complete 105 service, must be connected in multiple to 110

terminals in both the primary selector switches and the connector switches, since it is through the former that the subscriber when calling reaches the central office, and it is through the connector switches that the central office when calling reaches the subscriber.

- Associated with each connector switch is an auxiliary or ringing selector switch.
- 10 The wiper of this switch sweeps over contacts connected to several ringing generators, each of which generates a particular distinctive character of current. At the several stations on a party line the bells are de-
15 signed and adjusted so as to respond selectively and exclusively, each to its own particular kind of current only. At the last stage in a connection, when the wanted subscriber's line has been picked out by the
20 connector switch, and the ringing selector has been set so as to bring into service the proper generator, the wiper of that switch is then automatically connected through the connector to the subscriber's line to ring his
25 bell. At all other times the ringing selector remains disconnected.

The primary selector switches are controlled by the subscribers in calling, through the medium of line relays at the central of-
30 fice which respond to the flow of current in the subscribers' lines, and which when so energized guide and direct the primary switch wipers to their respective line contacts. A calling subscriber therefore gains
35 access to the first selector trunks in the central office by his own act alone. In order to continue the connection however, from the first selector trunk to the wanted subscriber, it is necessary to actuate a selector switch,
40 and a connector switch. The type of switch employed in this system is electromagnetically driven by means of current impulses of predetermined number sent in predetermined groups, which move the switch wipers step by step over the bank contacts.
45 These impulses are supplied, and the switches are controlled, by operators, at the central office, who for that purpose are given access through secondary selector switches
50 to the first selector trunks, whereby they are enabled both to receive their orders from the calling subscribers, by way of the primary selectors, and to send impulses to the first selector and succeeding switches, for the
55 purpose of making the desired connection. The secondary selector switches as will pres-
60 ently be seen, are initially responsive to the subscribers' acts in calling. In fact, broadly speaking, their operation is the same as that of the primary selector, the flow of current in a calling subscriber's line and in the first selector trunk connected thereto causing a secondary selector switch wiper to be guided and directed automatically to a con-

tact in its bank which is connected to the 65 first selector trunk in question.

In order to select and transmit the proper impulses for line selection I provide each operator with a key-set mounted on a suitable desk, and having associated with it cer-
70 tain signals which guide the operator in the performance of her duties. The key-set in general appearance and arrangement is quite similar to the key board of an adding machine or typewriter, consisting of a num-
75 ber of strips of ten keys each, numbered from one to naught in each vertical row. One of the signals associated with these keys is a calling lamp, which is lighted au-
80 tomatically when the key set becomes connected through the secondary switch to a first selector trunk already connected to a subscriber's line through a primary selector switch. Observing the signal, the operator asks the subscriber for the number wanted,
85 and proceeds to depress the corresponding keys or buttons. She then presses a separate starting key, and groups of impulses, corresponding to the buttons depressed, will thereupon be transmitted through the key-
90 set, through the secondary selector switch and through the selector trunk to the selector switch, causing the following operations:
(1) The selector switch is stepped around to the contact of a connector trunk leading to
95 a connector switch of the hundreds group corresponding to the first digit set up, (this particular connector containing terminals of the line wanted); (2 and 3) the connector switch is then stepped around in response to
100 the second and third groups of impulses to pick out the terminals of the line wanted; and (4) the associated ringing selector having been set in response to the operation of the impulses, the wanted subscriber's bell is
105 automatically rung.

Reference has been made above to "hundreds groups" of circuits. This particular switching system is known as a percentage trunking system. That is to say, the connection between any two lines is effected by successive steps or successive acts of subdivision. Obviously therefore, access could be had to any desired line by picking out a connector of the hundreds group in which the
110 line number occurred. That connector would then actually contain terminals of the wanted lines. Of course in practice the
115 wiring between the different groups of switches is quite complicated because of the large number of trunk wires employed to furnish the various combinations required between the switches, but the theory is quite simple, and is well enough illustrated in Fig. 1.

As soon as one of the subscribers at the left of Fig. 1 has become connected in the manner stated with one of the subscribers at

the right, it is unnecessary and in fact undesirable for the operator to remain longer in connection with them, and means are provided for automatically cutting off and restoring the secondary selector switch as soon as this condition is brought about. Thererafter all the switches in use between the two subscribers are under their own control, and when they finally hang up their 10 receivers the several switches are automatically restored, the connection is broken, and all parts resume the positions of idleness diagrammatically illustrated in Fig. 1.

It will be noted after reading the foregoing that portions of the apparatus and circuits at the central office are common to all or a number of subscribers' lines, whereby confusion might arise from simultaneous connection of more than one line to the same 20 trunk, more than one trunk to the same line, more than one trunk to the same operator, or more than one operator to the same trunk. Special provision is made however, to prevent this. At the left of Fig. 1, I have indicated what I call a primary distributing switch and a secondary distributing switch. The first of these contains in its banks testing terminals of the primary switches or selector trunks. It is actuated in response 30 to the subscribers' calls, and always acts to select and start up an idle switch and trunk for connection with the calling line. There is only one distributing switch for all the primary selector switches serving the same 35 group of subscribers, hence only one switch can be started at a time, and this prevents more than one trunk being connected to the same line. In going to the line, the action of the primary switch is to test over its bank 40 contacts until it reaches a contact which has had its condition changed, due to current flowing in the calling line. If more than one line is calling, the switch will stop at the first one to be reached, and thereafter the 45 distributing switch will start another primary selector to search for the second calling line, whereby it is impossible for more than one line to get on the same trunk.

The secondary distributing switch performs the same functions with respect to the operators' or secondary selector switches, and is actuated also in response to the subscribers' calls, so as to start only one secondary selector switch at a time for any one group of 55 trunks.

The foregoing is an outline description of the apparatus and operations involved in the establishment of a telephone connection between two subscribers. For establishing a 60 broadcast service connection with a subscriber, the same apparatus and operation is involved except that for this purpose the special broadcast service connector trunks are provided each containing an amplifying 65 tube or tubes and arranged to form a group

which is reached only and always through a special group of call numbers for example, the tenth group. The connector switches of these broadcast service trunks are the same as those of the telephone service connector 70 trunks except that their bank contacts form multiple taps from a set of broadcast or program busses and trunks.

Thus a subscriber desiring broadcast service simply calls for a number in the tenth group representing the number of the program bus or trunk with which he desires connection. Being in the tenth group, the connection is made through a broadcast service connector trunk containing an amplifier tube or tubes so that matter transmitted through said busses or trunks will be amplified on to the subscriber's line through the connection established through the selector switch. 85

The switching system or telephone exchange system herein shown, excepting those portions in the special group (tenth group) assigned to broadcast distribution, is the same as that shown and described in the patent above referred to and to which reference is to be had for a detailed showing and description of the switches herein shown diagrammatically. It suffices here to point out that the selector and connector switches are of the two motion type in which the movable contact wipers are arranged to have first a rotary motion to bring them in line with any one row of a number of vertical rows of contacts and then a vertical motion to bring them into operative engagement with any set of contacts in that vertical row, suitable off normal or foot-step switches being provided, operable upon the first rotary or vertical movements, respectively, of the switch, as well as suitable rotary and vertical stepping magnets and a release magnet, the general function and operation of which elements are well understood by those skilled in the art. 100

As the apparatus and operation involved in the establishment of a connection for broadcast service is the same as that for a straight telephone connection except for the substitution for a telephone connector 115 trunk of a broadcast service trunk, the portion of the system involved in a telephone connection will first be described and as detailed description of the circuit connections and apparatus involved in such connection is given in the patent above referred to a description of operation will suffice for a clear understanding by those skilled in the art to which the invention pertains.

In establishing a straight telephone connection the operation is as follows, reference being had to Figs. 2 to 7. 125

The subscriber at station A desiring a connection lifts receiver R from hook H which bridges his telephone across line wires 1-2, 130

energizing relays R^1 and R^8 by way of B, 19, 20, R^3 , 21, R' , 22, r^{21} , 1, station A, 2, r^{22} , 23, ground to battery. Relay R' locks to ground through r^{11} , 24, and r^{23} , and connects ground to individual test contact c^{25} through 25 and r^{12} , while R^3 connects ground to row test contact c^{26} through 26 and r^{31} and completes circuit of ground lamp L and relay R^4 the former from B, 19, 27, L, 28, 10 r^{32} , ground to battery, the latter from B, 19, 29, R^4 , 30, r^{33} , to ground. Lamp L lights, and relay R^4 completes circuit of stepping magnet M to interrupter I for intermittent energization over the path, B, 19, M, 31, 15 r^{51} , 32, r^{41} , 33, I to ground. Magnet M moves switch S step by step until wiper ws engages a contact s connected to relay R^{13} (Fig. 3) of an idle primary selector trunk, whereupon relays R^5 and R^{13} , (Figs. 2 and 20 3) are energized by current through B, (Fig. 3), 34, 35, 36, r^{13} , 38, (38 Fig. 2), s , ws , 39, R^5 , 40, r^{42} , to ground. Relay R^5 opens circuit of magnet M at r^{51} , locks itself to ground through r^{52} and completes circuit of R^{11} over 25 path B, 19, 41, R^{11} , 42, r^{53} and ground. Relay R^{13} locks itself to battery through r^{131} , 43, r^{421} , 44, and 34 to B; connects battery to one terminal of relay R^{12} , through 34, 35, r^{132} , 45, 46, r^{152} , 47, and 48; and also completes circuit of rotary relay R^{18} through 30 r^{132} and interrupter I, so that this relay is energized intermittently, its circuit being: B, 34, 35, r^{133} , 45, 46, r^{152} , 47, 49, 50, R^{18} , 51, r^{121} , 52, r^{132} , I to ground. At each actuation 35 of relay R^{18} magnet M⁵ is energized by current from B, 34, 57, contacts 58 of foot step switch S⁴, 59, M⁵, 53, r^{181} , ground, stepping primary selector switch S⁴ around until wiper w^{26} engages row test contact c^{26} 40 whereupon relay R^{12} is energized over circuit B (Fig. 3), 34, 35, r^{133} , 45, 46, r^{152} , 47, 48, R^{12} , 49, w^{26} , c^{26} , (Fig. 2) 26, r^{21} , ground to battery. Relay R^{12} locks itself to ground through r^{122} , connects test wiper f^{25} to sleeve 45 relay R^{15} through 54, r^{123} and 55, and shifts interrupter I from rotary relay R^{18} to vertical relay R^{19} at r^{121} , so that R^{19} is intermittently energized over the circuit: B, 34, 35, r^{133} , 45, 46, r^{152} , 47, 49, R^{19} , 56, r^{121} , 52, 50 r^{132} , I, ground, to battery. At each actuation 55 of relay R^{19} vertical magnet M⁶ is energized over the path B, 34, 60, M⁶, 61, r^{191} to ground, stepping switch S⁴ up until wiper w^{25} engages individual test contact c^{25} (Fig. 2) whereupon sleeve relay R^{16} is energized over the circuit: B, (Fig. 3) 34, 35, 62, R^{16} , 55, r^{123} , 54, w^{25} , c^{25} , (Fig. 2), 25, r^{12} (of relay R'), ground to battery. Relay R^{16} connects battery to trunk conductor 7, by way of 60 r^{151} , 63, 64, r^{141} , 65, and resistance r , and at the same time opens the circuit of relay R^{12} at r^{152} . Relay R^{12} opens circuit of vertical relay R^{19} and magnet M⁶ is de-energized, which permits wiper w^{25} to stop on contact 65 c^{25} , wipers w^3 and w^4 engaging contacts c^3 and c^4 , respectively. Tip relay R^{14} is now energized through subscriber's telephone in series with R^{15} . Simultaneously with the selection of the calling line as described, distributing switch S², (Fig. 2) is stepped 70 around in search of an idle secondary selector, by magnet M² in circuit: B, 19, 41, 66, 67, 68, r^{91} , 69, M², 70, r^{111} , 71, I to ground. Switch S² continues to step around until wiper arm ws^{200} engages a contact s^{200} connected to an idle secondary selector, whereupon relays R^{10} and R^{32} , (Figs. 2 and 5) are energized in series, the circuit being: B, (Fig. 5), 86, springs 73-74 of operator's jack J, 75, springs 76-77 of foot step switch F⁸, 78, R^{32} , 79, through Fig. 3 into Fig. 2, s^{200} , ws^{200} , 80, 81, R^{10} , 82, r^{112} to ground. The actuation of relay R^{10} causes the energization of relay R^9 , the circuit being: B, 19, 41, 66, 67, r^{101} , 83, 84, R^9 , 85, r^{113} to ground. Relay R^9 locks itself to battery through r^{92} , and opens circuit of magnet M² at r^{91} , whereupon switch S² comes to rest with wiper arms ws^2 , ws^{20} and ws^{200} resting on contacts s^2 , s^{20} , and s^{200} , respectively. 90

The attraction of armature r^{91} of relay R^9 connects battery to wire 99 which completes part of the row test circuit and the attraction of armature r^{92} completes the circuit of relay R^8 as follows: B, to R^8 , 223, r^{93} to 95 ground. Relay R^8 , grounds wire 80, shunting relay R^{10} out of series with relay R^{32} (Fig. 5), the circuit of the latter relay now going direct to ground by way of wire 80 and armature r^{82} . Relay R^{32} (Fig. 5) completes the circuit of rotary relay R^{39} through interrupter I so that said relay is intermittently energized by current over B, 86, 87, r^{301} , 88, r^{311} , 89, R^{39} , 90, r^{321} , I to ground. Relay R^{32} also connects one terminal of relay R^{30} to ground through 91 and r^{322} , and locks itself to battery through 92, r^{323} , 93, r^{302} , 87, 86, B. Each actuation of relay R^{39} energizes rotary magnet M¹⁸ through B, 86, 94, M¹⁸, 95, r^{301} to ground. Magnet M¹⁸ 100 steps switch S⁸ around until wiper ws^2 engages contact s^{82} . The first rotary step of the switch S⁸ disconnects contacts 76 and 77 of switch F⁸ and connects contacts 76 and 290, which opens the initial energizing circuit of relay R^{32} , (that relay, however, remaining energized through its locking circuit) and closes the circuit of off-normal lamp L⁷ as follows: B, 86, 73, 74, 75, 76, 290, L⁷ to ground. When wiper w^{82} engages 105 contact s^{82} the relay R^{31} is energized over the path: B, ground to r^{322} (of relay R^{32}), 91, 96, R^{31} , 97, w^{82} , s^{82} , 98, through Fig. 3 into Fig. 2, s^{20} (in switch S²), ws^{20} , 99, r^{91} , 68, 67, 66, 41, 19, battery. Relay R^{31} locks itself to battery through: 100, r^{312} , 101, 88, r^{301} , 87 and 86, opens circuit of relay R^{39} and closes circuit of relay R^{40} at r^{311} . Relay R^{39} opens circuit of magnet M¹⁸ 110 at r^{301} , which stops switch S⁸ with wiper 115 w^{82} . The second rotary step of the switch S⁸ disconnects contacts 76 and 77 of switch F⁸ and connects contacts 76 and 290, which opens the initial energizing circuit of relay R^{32} , (that relay, however, remaining energized through its locking circuit) and closes the circuit of off-normal lamp L⁷ as follows: B, 86, 73, 74, 75, 76, 290, L⁷ to ground. When wiper w^{82} engages 120 contact s^{82} the relay R^{31} is energized over the path: B, ground to r^{322} (of relay R^{32}), 91, 96, R^{31} , 97, w^{82} , s^{82} , 98, through Fig. 3 into Fig. 2, s^{20} (in switch S²), ws^{20} , 99, r^{91} , 68, 67, 66, 41, 19, battery. Relay R^{31} locks itself to battery through: 100, r^{312} , 101, 88, r^{301} , 87 and 86, opens circuit of relay R^{39} and closes circuit of relay R^{40} at r^{311} . Relay R^{39} opens circuit of magnet M¹⁸ 125 at r^{301} , which stops switch S⁸ with wiper 130 w^{82} .

w^{82} engaging contact s^{82} . As circuit of relay R^{40} is completed at r^{811} said relay is intermittently energized through: B, 86, 87, r^{801} , 88, r^{811} , 102, R^{40} , 103, 90, r^{821} , I, ground. Each actuation of relay R^{40} energizes vertical magnet M^{14} through: B, 86, M^{14} , 104, r^{401} , ground. Magnet M^{14} steps switch S^8 up until wiper w^{84} engages contact s^{84} , whereupon relay R^{30} is energized through: B, ground to r^{822} (relay R^{32}), 91, R^{30} , 105, w^{84} , s^{84} , 45 (45 Fig. 3) r^{183} , 35, 34, battery. Relay R^{30} opens locking circuit of relay R^{32} at r^{802} , also opens circuit of relay R^{40} at r^{801} , r^{401} of relay R^{40} opens the circuit of vertical magnet M^{14} which stops switch S^8 with wipers w^{80} , w^{81} , w^{83} , and w^{84} , on contacts s^{80} , s^{81} , s^{83} , and s^{84} . (Wiper w^{82} is raised off row contacts by first step.) Wiper w^{83} engaging contact s^{83} , (Fig. 5) relays R^{34} and R^{42} , (Figs. 5 and 3) are energized through: B, (Fig. 3), 34, 35, 36, r^{151} , 63, 106, R^{42} , 107, (107 Fig. 5), s^{83} , w^{82} , 108, r^{813} , 109, r^{851} , 111, 112, R^{34} , 113, r^{831} , 114, r^{861} , 115, r^{852} , 116, r^{822} , ground. Relay R^{42} , when actuated, opens series circuit of relays R^5 and R^{18} (Figs. 2 and 3) at r^{421} . Relay R^{18} disconnects interrupter I at r^{182} and relay R^5 (Fig. 2) opens circuit of relay R^{11} at r^{68} . Relay R^{11} deenergizing opens circuits of magnet M^2 , relay R^9 and relay R^{10} , while relay R^8 , its circuit opened at r^{68} , opens circuit of stepping magnet M' at r^{81} . This prepares distributing switches S and S^2 , with their relays, for another call. Relay R^{34} becoming energized closes circuit of night alarm N through: B, 86, 110, 117, 118, r^{841} , 119, N, to ground; closes circuit of guard lamp L^2 (Fig. 6) through B (Fig. 5), 86, 110, 117, 118, r^{842} , 120, 121, (121 Fig. 6), L^2 to ground; closes circuits of service meter E (Fig. 5) through B, armature r^{843} , 122, 242, and magnet of service meter E to ground; and line lamp L^3 (Fig. 6) through B (Fig. 5), r^{843} , 122, 123, (123 Fig. 6), L^3 to ground. The operator, perceiving the signal, depresses listening key LK (Fig. 6) energizing listening relay R^{38} (Fig. 5) through: B, (Fig. 5), 86, 87, r^{801} , 88, 101, r^{812} , 124, R^{38} , 125, (125 Fig. 6), contacts of key LK, 126 to ground. Relay R^{38} energizing, opens series circuit of relays R^{34} and R^{42} at r^{881} and locks itself to ground through r^{881} , and 114, as previously traced. Relay R^{42} deenergizing, opens circuit of relay R^{41} at r^{421} . Relay R^{38} completes the operator's listening circuit as follows: receiver OR, 127, tip p , spring j , 128, r^{882} , 129, 131, w^{80} , s^{80} , 130 (130 Fig. 3), r^{411} , 9, r^{422} , 7, condenser C', 5, w^8 , c^8 , (Fig. 2), 3, r^{21} , over subscriber's line and back to r^{22} , thence through 291, 4, c^4 , w^4 , (Fig. 3), 6, condenser C', 8, r^{422} , 10, 134, r^{412} , 135, (135 Fig. 5), s^{81} , w^{81} , 132, 136, r^{832} , 137, coil IC, 138, jack spring j' , plug sleeve p' , 139, receiver OR.

Should the calling subscriber hang up his

receiver before the operator is connected, tip relay R^{14} (Fig. 3) is deenergized, its circuit being open at the subscriber's switch hook contact, and sleeve relay R^{15} remaining energized in series with cut-off relay R^2 (Fig. 2), energizing circuit of relay R^{38} (Fig. 5) is completed as follows: B, (Fig. 3) 34, 36, r^{151} , 63, r^{141} , through resistance r , trunk conductor 7, r^{422} , 9, r^{811} , 130 (130 Fig. 5), s^{80} , w^{80} , 131, 129, r^{833} , 128, 154, R^{38} to ground. Relay R^{38} energizing, connects operator's tone-test circuit T^t through 155 and 137 to operator's receiver, and the operator being thus notified that the calling subscriber has disconnected, actuates the "release and trunk start" key RK, (Fig. 6) whereupon relay R^{37} (Fig. 5) receives current through: B, 86, 110, 156, R^{37} , 157, (157 Fig. 6) key RK to ground. R^{37} then energizes starting relay R^{36} in series with relay R^{42} , (Fig. 3), through: B, (Fig. 3), 34, 36, r^{151} , 63, 106, R^{42} , 107, (107 Fig. 5), s^{83} , w^{83} , 108, r^{813} , 109, r^{851} , 111, 141, R^{36} , 140, 158, r^{871} , 159, 157 to ground through RK. Relay R^{42} energizes relay R^{41} which through armatures r^{411} and r^{412} connects impulse sending wires 130 and 135 to tip and sleeve conductors 9 and 10 respectively. The circuit of relay R^{41} is: B, 34, 44, r^{421} , R^{41} , 143 contacts 144 and 145 of foot-step switch F^6 to ground. Relay R^{36} being energized, opens the locking circuit of listening relay R^{38} at r^{861} and locks itself through r^{861} , 115, r^{852} , 116, r^{822} , to ground; and also establishes a locking circuit for relay R^{37} through 159, r^{871} , 158, 140, r^{861} to ground over the same path traced for locking circuit of relay R^{36} . Armature r^{862} closes circuit of guard lamp L^2 (Fig. 6) through: B, (Fig. 5) 86, 110, 117, r^{862} , 150, 121, L^2 to ground, and armature r^{863} partially closes circuit magnet M^{15} so that when cam disk D^{11} (Fig. 6) closes contacts d^{11} , said magnet is momentarily energized, stepping switch S^8 forward one step. The circuit of magnet M^{15} is: B, (Fig. 5), 86, 110, 117, M^{15} , 153, r^{855} , 152, r^{863} , starting wire 151, (151 Fig. 6), contacts d^{11} , to ground.

Immediately after switch arm w^8 engages contact 1^{83} , a number of ground impulses come from the sending machine over wire 173 (as hereinafter described) by way of contact 1^{83} , wiper-arm w^8 , trunk-conductor 131, w^{80} , s^{80} , 130, (130 Fig. 3), r^{411} , relay R^{21} to battery and ground. Each actuation of relay R^{21} closes circuit of magnet M^8 at r^{211} , which steps the switch S^8 forward one step, springs 175 and 176 of switch F^6 being closed at the first rotary step. The closure of springs 175 and 176 energizes release magnets M^8 and M^4 of the primary and first selector switches S^4 and S^5 , through 106, 177, r^{142} , 178, 179, M^8 and M^4 in multiple, to B. These magnets restore their respective switches to normal position. The circuit of sleeve relay R^{15} is now open at w^4 , and its

armature r^{151} , opens the series circuit of relays R^{42} , and R^{36} (Figs. 3 and 5). Relay R^{36} opens at r^{361} the locking circuit of relay R^{37} . As wiper arm ws^{300} is resting on contact 5 1^{s300} and armature r^{362} of relay R^{36} is retracted, the retraction of armature r^{372} , of relay R^{37} , closes circuit of relay R^{35} as follows: B, 86, 110, 117, r^{362} , 163, 161, r^{372} , 293, 1 s^{300} , ws^{300} , 164, R^{35} to ground. Armature 10 r^{352} of relay R^{35} connects one terminal of stepping magnet M^{15} to interrupter I for intermittent energization over the path: B, 86, 110, 117, M^{15} , 153, r^{353} , 152, r^{362} , 163, 162, contacts 3^{s300} to 5^{s300} and so on 15 and ws^{300} over their respective bank contacts. After wiper arm ws^{300} leaves contact 2^{s300} and sweeps over contacts 3^{s300} to 5^{s300} relay R^{35} is kept energized through B, 86, 110, 117, r^{362} , 163, 162, contacts 3^{s300} to 5^{s300} and so on 20 to as previously traced. When wiper arm ws^{300} reaches contact 6^{s300} the circuit of relay R^{35} is again changed and said relay is energized while the arm sweeps over contacts 6^{s300} to 9^{s300} , through: B, 86, 110, 166, 6^{s300} to 9^{s300} , ws^{300} , 164, and so on as previously traced. When wiper arm ws^{300} passes off the last contact 9^{s300} it opens the circuit of relay R^{35} , which disconnects magnet M^{15} from interrupter I at r^{353} and stops switch S^3 with its 25 wiper arms ws^3 , ws^{30} and ws^{300} clear of all contacts. Shortly before switch S^3 comes to normal position, contact springs 168 are momentarily closed by a cam on the switch spindle and release magnet M^{16} is energized 30 through: B, 86, 169, 170, M^{16} , 172, 168, ground. Magnet M^{16} restores switch to normal position, ready for another call.

If the calling subscriber remains on the line, the operator, on ascertaining the number wanted sets up the same on her key set, (Fig. 6) by depressing the key in strip K^1 corresponding to the first digit, that in the strip K^2 corresponding to the second digit, that in the third strip K^3 corresponding to 35 the third digit, and that in the strip K^4 corresponding to the particular ringing generator to be selected, and then actuates starting key, SK, whereupon starting relay R^{36} (Fig. 5) is energized in series with trunk 40 cut-off relay R^{42} (Fig. 3) through: ground, 126, (Fig. 6) key SK, 140, (140 Fig. 5), R^{36} , 141, 111, r^{351} , 109, r^{313} , 108, ws^3 , s^{33} , 107 (107 Fig. 3), R^{42} , 106, 63, r^{161} , 34, battery to ground. Relay R^{42} opens trunk conductors 45 9-7 and 10-8 at r^{422} and r^{423} , and energizes relay R^{41} through: B, 34, 44, r^{421} , R^{41} , 143, contacts 144 and 145 of switch F^5 to ground. Armatures r^{411} and r^{412} connect the impulse 50 wires 130 and 135 to rotary and vertical relays R^{21} and R^{20} , respectively, while armature r^{413} connects conductor 147 to one terminal of relay R^{41} through contact 146. Starting relay R^{36} (Fig. 5) takes ground off relay R^{35} through 114, at r^{361} , and locks itself 55 through r^{361} and 115 to ground as previously traced. Armature r^{362} maintains the circuit of the guard lamp through B, 86, 110, 117, r^{362} , 150, 121, guard lamp to ground, as previously traced. Armature r^{363} connects starting wire 151 to stepping magnet M^{15} and partially completes a connection from B, (Fig. 5) 86, 110, 117, M^{15} , 153, r^{353} , 152, r^{363} , starting wire 151 (151 Fig. 6) contact springs d^{11} , to ground; so that when cam disk D^{11} (Fig. 6) closes contacts d^{11} , said magnet is momentarily energized, stepping switch S^3 forward one step. Immediately after cam D^{11} (Fig. 6) has passed under the contacts d^{11} , the number cams D' to D^{10} inclusive, pass under their respective contact 80 springs d' to d^{10} inclusive, the cam D' maintaining the closure of contact d' during one closure of the interrupter contact springs d' , the cam D^2 maintaining the closure of its contact springs d^2 during two closures of 85 said interrupted contacts, and so on to the cam D^{10} , which maintains the closure of its contact springs d^{10} during ten closures of the interrupted contact springs. During the passage of the number cams under their contact springs, ground impulses (corresponding in number to the first digit of the wanted line) are sent over the hundreds impulse wire 173 to the rotary relay R^{21} of the first selector switch S^6 , (Fig. 3). Assuming for 90 example, that the number wanted is 246-3, relay R^{21} will be momentarily energized two times, through: ground, d^1 , 190, d^2 , 191, 192, 193, k^{12} of strip K' , 173, (173 Fig. 5), 1^{s33} , ws^3 , 131, ws^0 , s^{30} , 130 (130 Fig. 3), r^{411} , R^{21} , 100 battery B to ground. Relay R^{21} intermittently energizes magnet M^8 which steps switch S^6 to the second row of contacts through which the connector containing wanted subscriber's line is accessible. At 105 the first rotary step of switch S^6 , contact springs 175-176 are closed, completing the circuit of "off-normal" lamp L^5 through B, 103, 104, L^5 , 105, 106, 176, 175, to ground; also partially closing the release circuit through 110 magnets M^3 and M^4 , hereinafter described. After the number cams have passed under their respective springs cam D^{11} again closes its contacts d^{11} stepping switch S^3 around to bring its wipers into engagement 115 with the next set of contacts. Wiper arms ws^3 , ws^{30} and ws^{300} of switch S^3 now engage their respective contacts 2^{s3} , 2^{s30} , and 2^{s300} , and cam D^{12} (Fig. 6) connects test impulse wire 189 through springs d^{12} , conductor 190 120 and springs d^1 to ground during ten closures of springs d^1 , whereupon vertical relay R^{20} (Fig. 3) is intermittently energized through: ground, d^1 , 190, d^{12} , 189 (189 Fig. 5), 2^{s30} , ws^{30} , 132, ws^1 , s^{31} , 135, (135 Fig. 3), r^{412} , 199, 125 R^{20} , 196, battery, to ground. Relay R^{20} intermittently closes circuit of magnet M^7 at r^{201} , stepping up wipers w^9 , w^{10} and w^{14} of the first selector switch S^6 to engage contacts c^{13} , c^{14} , and c^{200} , respectively, leading to a 130

connector trunk (Fig. 4). At the first vertical movement of the spindle of switch S^5 the circuit of relay R^{41} is opened at contact springs 144 and 145 of switch F^5 , and should the connector trunk (Fig. 4) be busy because of the wipers of another first selector switch resting on the multiples of contacts c^{200} , relay R^{41} would remain energized through B (Fig. 3), 34, 44, r^{412} , R^{41} , 146, r^{413} , 147, w^{147} , c^{200} (Fig. 4) to the multiples of c^{200} and thence through the circuit of the other first selector by way of its wiper w^{147} (as in Fig. 3), 147, r^{413} , ground, to battery. The armature r^{412} of relay R^{41} , remaining attracted 15 permits the next test impulse to energize vertical relay R^{20} stepping the wipers up to the next set of contacts, and so on until an idle connector is reached, when, relay R^{41} being deprived of ground, releases its armatures. 20 The armature r^{412} , disconnects impulse wire 135 from the relay R^{20} , stopping switch S^5 with its wipers w^9 , w^{10} , and w^{147} on contacts c^{13} , c^{14} , and c^{200} , respectively, of the connector trunk (Fig. 4). The impulse wires 130 and 135 are now connected to the tip and sleeve conductors 9 and 10 through armatures r^{411} and r^{412} respectively, and contact c^{200} (Fig. 4) and its multiples are connected to ground through: w^{147} (Fig. 3), 147, and r^{413} . After cam D^{12} (Fig. 6) has passed springs d^{12} , starting cam D^{11} , again closes springs d^{11} , steps switch S^3 around to bring its wipers into engagement with the third set of contacts. Wiper arms ws^8 , ws^{30} , and ws^{300} now engage their respective third contacts. The number cams now pass under their respective contact springs for the third time and send impulses, corresponding in number to the desired ringing generator (in this case No. 3), to relay R^{23} (Fig. 4), through: ground, springs d^1 (Fig. 6), 190, d^3 , 198, 203, k^{43} , 197 (197 Fig. 5), 3^{83} , ws^3 , 131, ws^{80} , s^{80} , 130, (130 Fig. 3), r^{411} , 9, w^9 , c^{13} , (Fig. 4), 16, r^{261} , 204, R^{23} , 205, B to ground. 45 Each actuation of relay R^{23} energizes magnet M^{11} of switch S^7 , through: B, 208, 209, 210, and 211, 212, 213, M^{11} , 214, 215, r^{231} to ground. Magnet M^{11} moves switch S^7 forward three steps, bringing wipers ws^7 , ws^{70} , and ws^{700} onto contacts 3^{87} , 3^{870} and 3^{8700} respectively. 50 The first actuation of R^{23} energizes R^{24} and R^{27} , the first through: B, 207, 205, r^{233} , 247, R^{24} , 202, 200, c^{200} , w^{147} , (Fig. 3) 147, r^{413} to ground, locking itself to battery through r^{241} , 250, r^{222} , 207; the second relay through: r^{232} (of relay R^{23}), 234, 230, R^{27} , 235, r^{252} , 236, 202, to ground, locking itself to battery through: 232, r^{271} , 233, r^{291} , 231. Cam D^{11} (Fig. 6), again closing contacts d^{11} moves switch S^3 one step bringing its wipers onto the fourth set of contacts. Wiper ws^{30} now engages contact 4^{830} and the number cams close their respective springs and send impulses to R^{22} (Fig. 4) through: ground, contacts d^1 , (Fig. 6) 190, d^4 , 225, 226, 227, k^{24} of strip K^2 , 224, (224 Fig. 5), 4^{830} , ws^{80} , 132, w^{81} , s^{81} , 135, (135 Fig. 3), r^{412} , 134, 10, w^{10} , c^{14} , (Fig. 4), 15, r^{282} , 228, R^{22} , 229, 230, r^{271} , 233, r^{291} , 231, battery to ground. Each actuation of R^{22} energizes magnet M^9 through: B, 208, 237, 239, M^9 , 240, r^{221} , ground. Magnet M^9 moves switch S^6 forward four steps bringing wipers w^{17} and w^{18} onto the fourth row of contacts, in which lie the wanted line contacts. 70 The first actuation of R^{22} opens the locking circuit of R^{24} at r^{222} . The first rotary step opens springs 210—211 and closes 210—246, which shifts battery lead 209 from M^{11} to M^{10} and lights lamp L^6 by current through: B, 210, 246, 264, r^{283} , L^6 to ground. Cam D^{11} (Fig. 6) again closes contacts d^{11} and sends one impulse over wire 151, actuating switch S^3 to step its wipers onto their fifth set of contacts. After cam D^{11} has passed contacts d^{11} , the number cams again actuate their respective spring contacts sending unit impulses through 241, (241 Fig. 5), 5^{83} , ws^3 , 131 to R^{23} (Fig. 4). Each actuation of relay R^{23} energizes M^{10} , through: B, 208, 209, 210, 246, 244, M^{10} , 243 r^{272} , 215, r^{231} , to ground. Magnet M^{10} is actuated six times, stepping wipers w^{17} and w^{18} onto contacts c^{17} and c^{18} (Figs. 4 and 7 respectively). 95 The first actuation of relay R^{23} again energizes R^{24} through r^{233} and R^{24} locks itself and opens the circuit through relays R^{25} and R^{26} to wipers w^{17} and w^{18} , at r^{243} and r^{241} to prevent affecting said relays while the wipers are passing over other line multiples. After the number cams pass their springs, and before cam D^{11} closes its springs, cam D^{13} closes spring d^{13} , sending a single test impulse through 292, (292 Fig. 5), 5^{830} , ws^{80} , 105 132, to R^{22} (Fig. 4), whereupon if the wanted line (Fig. 7) is busy, with wipers w^{17} , w^{18} , of another connector switch, or w^8 , w^4 of a primary selector switch, resting on multiples of contacts c^{17} , c^{18} , the test relay R^{20} (Fig. 4) is energized, in the first case through: ground, r^{413} (Fig. 3), 147 w^{147} , c^{200} (Fig. 4), 200, 201, R^{20} , 251, r^{223} , 252, r^{281} , 253, 100 18, w^{18} , c^{18} , (Fig. 7) to the multiple of c^{18} on which the other connector switch wipers are resting, thence through that connector by way of w^{18} , 18, 253, r^{281} , 252, r^{223} , 259, R^{26} , r^{241} , 250, r^{222} , 207, B, to ground, in the second case: R^{29} , c^{18} , thence through the multiple of c^{18} , on which wiper w^4 , of a primary selector 110 is resting 294, r^{123} , 55, R^{15} , 34, B, to ground. Relay R^{29} when energized locks itself to battery through 262, r^{231} , connects the busy back B² to trunk conductor 16, through r^{292} and closes the release circuit of S^6 through: B, 208, 209, 210, 246, 264, 265, r^{293} , 267, 269, M^{12} to ground. M^{12} then releases the connector switch S^6 . After this impulse relay R^{22} is deenergized, and completes the restoring circuit of switch S^7 , through: B, r^{222} , 250, r^{241} , 130

r^{275} , 271, 251, 212, 213, M^{11} , 214, r^{272} , 273, ws^{700} , s^{700} , 274, I to ground.

Magnet M^{11} is intermittently energized until switch S^7 reaches normal position when its circuit is opened between ws^{700} and s^{700} .

The test relay R^{29} remains locked, holding busy-back B^z on trunk conductor 16, to signal the calling subscriber, (Fig. 2), who then hangs up his receiver, opening circuit

10 of R^{14} (Fig. 3) which deenergizes and releases magnets M^3 and M^4 of switches S^4 and S^5 through ground, 175, 176, 106, 177, r^{142} , 178, 179, M^3 and M^4 , (in multiple), B, to ground. The switch S^5 in restoring opens

15 the circuit of R^{28} (Fig. 4) at c^{200} and w^{147} (Fig. 3) and the busy-back is disconnected.

If the wanted subscriber is not busy, R^{27} remains locked, and after the test impulse R^{22} deenergizes, which energizes R^{26} (Fig. 4)

20 and R^{43} (Fig. 7) in series, through: B, (Fig. 4), r^{222} , 250, r^{241} , R^{26} , 259, r^{223} , 252, r^{281} , 253, 18, w^{18} , c^{18} , (Fig. 7) 255, R^{43} to ground. Relay R^{26} closes trunk conductors 15—17 and 16—18 at r^{262} and 261, respectively, while

25 R^{43} (Fig. 7) connects line terminals 256 and 257 to extensions 254 and 255. Simultaneously with the energization of R^{26} and R^{43} , ringing relay R^{28} is connected through: B, r^{222} , 250, r^{241} , r^{273} , 277, r^{242} , 278, R^{28} , inter-

30 ruptor I^2 to ground.

Immediately after the test impulse cam D^{11} (Fig. 6) causes contacts d^{11} to send an impulse over wire 151, stepping switch S^3 (Fig. 5.) forward one step bringing its

35 wipers onto the sixth contact set. When ws^{300} engages contact $6s^{300}$, the restoring relay R^{35} is energized through: B, 86, 110, 166, $6s^{300}$ to $9s^{300}$, 164, R^{35} , to ground. Relay R^{35} opens circuit of R^{36} and R^{42} ,

40 (Figs. 5 and 3 respectively) at r^{361} and r^{352} , while r^{353} connects magnet M^{15} for intermittent energization through: B, 86, 110, 117, M^{15} , 153, r^{358} , I to ground. Magnet M^{15} steps switch S^3 forward, holding

45 R^{35} energized through ws^{300} and contacts $6s^{300}$ to $9s^{300}$, until the wipers have reached normal position, as shown. The secondary selector switch S^8 is restored by the cam on the switch S^3 , in passing, and the operator's circuit is ready to receive another call.

50 Ringing relay R^{28} is intermittently energized by interrupter I^2 to ring subscriber A^3 , (Fig. 7) through circuit: G^3 , 279, s^{370} , ws^{70} , 280, r^{282} , 17, w^{17} , c^{17} , (Fig. 7) 254, r^{431} , 256, 282, ringer Q^3 , C^{30} , 283, 257, r^{432} , 258, 255, c^{18} , w^{18} , (Fig. 4) 18, 253, r^{283} , resistance r' , 285, 208, 206, B to ground, and generator G^3 . At each energization of relay R^{28} the circuit of lamp L^3 is opened at r^{288} . When the called subscriber A^3 takes down his receiver, he bridges his telephone across the line, and at the next non-ringing interval the circuit of the tip relay R^{25} is closed through: B, (Fig. 4) through R^{28} to c^{18}

(Fig. 7), 255, r^{432} , 257, 283, H^{30} , telephone at A^3 , 286, 256, r^{431} , 254, c^{17} , w^{17} (Fig. 4), 17, r^{282} , 287, R^{25} , r^{243} , r^{221} , to ground. Relay R^{25} opens circuit of R^{27} at r^{252} , relay R^{27} opens circuit of ringing relay R^{28} at r^{273} , and the ringing ceases.

The calling, and called subscribers A and A^3 , respectively, are now connected for conversation over the circuit indicated in heavy lines in Figs. 2, 3, 4 and 7.

75 Relay R^{25} connects test contact c^{200} through: c^{200} , 200, 202, 236, r^{252} , to ground side of battery, which renders the trunk busy in case the calling party should hang up first. At the end of the conversation, when calling subscriber A hangs up his receiver the circuit of the tip relay R^{14} (Fig. 3) is opened, whereupon armature r^{142} falling back, closes the circuit of release magnets M^3 and M^4 of the switches S^4 and S^5 , which return to their normal position. When called subscriber A^3 hangs up his receiver, the circuit of tip relay R^{25} (Fig. 4) is opened, whereupon armature r^{251} , falling back, completes the restoring circuit of switch S^7 , said switch is restored, and when wiper arm ws^7 engages contact $9s^7$ (which occurs just before the switch reaches its normal position) the circuit of release magnet M^{12} is completed as follows: battery B , 207, 289, w^s , 290, 269, M^{12} , ground, to battery. The connector switch S^6 then returns to its normal position.

80 In the establishment of a connection for furnishing broadcast service, the operation and the apparatus employed is the same except that the connection is made through the line tube connector trunk or link circuit, Fig. 8, to one of the program busses or trunks, the subscriber calling from his broadcast receiving set or from an extension telephone set and receiving the program on the loud speaker receiver of this set.

85 The subscriber's broadcast receiver set (Fig. 2) comprises a loud-speaker receiver 307 connected to the secondary winding of a transformer 308 whose primary winding is connected with the line extensions or branch wires 309—310 in series with a transmitter 311 and switch H^2 , the line extensions 309—310 being extensions of the line conductors 1—2, respectively. Thus the broadcast receiving set is connected as an extension telephone set.

90 The line tube connector trunk and switch of Fig. 8 is similar to the connector trunk and switch of Fig. 4 but much more simple as the ringing, testing and busy-back signaling circuits and apparatus are omitted. Here the tip and sleeve trunk circuits are extended from the contacts c^9 — c^{10} , multiplied in the banks of selector switches such as that of Fig. 3, to the wipers w^{30} — w^{40} through the contacts of a disconnect-relay R^{52} , and coupling transformer 315 to line tube 316.

The relay R^{52} is arranged to open the trunk circuit between the transformer and the bank contacts when energized to normally maintain connection of the rotary and vertical repeating relays $R^{50}-R^{51}$ to the tip and sleeve conductors 301-302 respectively. The repeat relays control the movements of the switch through the rotary and vertical driving or stepping magnets $M^{20}-M^{21}$ in a manner similar to that described in connection with Fig. 4, the rotary magnet M^2 being also controlled through vertical foot-step switch 313 operable upon the first vertical movement of the connector switch S^{11} . The magnet M^{22} is the release magnet for the switch S^{11} and is controlled jointly by a starting and holding relay R^{54} and a rotary foot-step switch 314 operable upon the first rotary movement of the switch. The relay R^{54} also controls the initial energizing circuit of the relay R^{52} through the vertical foot-step switch 313, the relay R^{52} having a locking circuit controlled through a normally closed contact of the rotary relay R^{50} . Relays $R^{52}-R^{54}$ jointly control the relay 53 for controlling the energization of the filament circuit of the line tube 316. Various detailed circuit connections and functions of the different relays and switches will be made clear in the description of operation which will follow later. Connector switch S^{11} is provided with a contact bank similar to that of the connector switch of Fig. 4, but instead of the contacts such as $c^{40}-c^{40}$ forming the terminals of subscribers' lines they form multiple connections to program busses and trunks 317, 318, 319, 320. The program busses such as 317-318 are supplied with matter to be distributed broadcast to the subscribers from a suitable source of supply, not shown, but which may be the audio output circuit of a radio receiving set or other program supply means such as those shown and described in my copending application Serial No. 10,916 filed February 21, 1925.

The program trunks such as 319 and 320 constitute trunk lines leading to other central stations for the purpose of receiving broadcast matter available at such other stations. These program busses and trunks are multiplied in the banks of the broadcast service connector switches S^{11} and are assigned to a given group or groups preferably the 10th hundreds group as here shown by way of example. The output terminals of the trunks of these connector switches therefore appear in the last or tenth vertical rows of the contact banks of the selector switches S^5 . All calls for numbers beginning with 10 (or zero on the operator's key set) such as 10-46 will be made through a broadcast service trunk and connector switch S^{11} with a line tube 116 included in the connection. Thus the operation in establishing a connection for broadcast service is the same as that for a straight telephone connection as described except that the connection is made through a connector switch S^{11} with the busy test and ringing omitted.

The operation of the system in the connection of a subscriber for broadcast service is as follows: The subscriber at substation A (Fig. 2) desiring broadcast service, closes the switch H^2 at his broadcast receiver extension set thus closing the line circuit by way of 309, primary of transformer 308, switch H^2 and extension 310. This closure of the line actuates the subscriber's line terminal apparatus at the central office in the same manner as that caused by closure of the line through his switchhook contact H and as previously described in detail for the establishment of telephone connection, and as previously described, connects the calling subscriber with an idle, operator's key set. The subscriber now gives the program number wanted, for example 10-46, which indicates that connection 42 in the 10th or broadcast service group is wanted. The operator thereupon depresses the 10th key or the key marked 0 in the hundredths row of her key set, which key in the drawing (Fig. 6) is connected at k^{10} in row K^1 , also key k^{24} in row K^2 , key k^{36} in row K^3 , and starting key SK in row K^4 . This results in different groups of impulses being sent through the operator's circuit of Fig. 5 and over the conductors 130-135 of Fig. 3 all in a manner similar to that set out in the description of operation for the establishment of a telephone connection. In the present example the order of impulses will run as follows: first, 10 impulses over conductor 130; second, 10 test impulses over conductor 135; third, 4 impulses over conductor 135; fourth, 6 impulses over conductor 130, and fifth, a single test impulse, now used as a shifting impulse, over the conductor 135. The first set of 10 impulses over the conductor 130 followed by the test impulses over conductor 135 will cause the selector switch S^5 to be first stepped around to the 10th row of contacts and then stepped up to select an idle connector trunk circuit and switch S^{11} (Fig. 8) permitting the relay R^{41} (Fig. 3) to become deenergized and extend the connections of conductors 130-135 through wipers w^0-w^{10} and contacts c^0-c^{10} to conductors 301-302, all in the manner similar to that previously described. Immediately the armature a^{413} of relay R^{41} (Fig. 3) falls back grounding the wiper w^{147} , a circuit is completed from this ground connection through wiper w^{147} , contact c^{147} (Fig. 8) relay R^{54} through battery B and back to ground, the completion of which circuit energizes relay R^{54} . Relay R^{54} attracting its armatures completes the ener-

gizing circuit of disconnect relay R^{52} from battery B through R^{52} , conductor 323, contact 325, r^{541} to ground and back to battery B. Attraction of armature r^{542} removes the 5 battery connection from release magnet M^{22} and partially completes the circuit of relay R^{53} . Energization of relay R^{52} disconnects the trunk conductors 301—302 from 303—304 and connects them to conductors 327—10 328, removes the ground connection from filament relay R^{53} at r^{522} and completes a locking or holding circuit for itself through r^{523} and armature r^{502} of relay R^{50} .

The third set of impulses, four in number, 15 now coming over conductor 135 pass through armature r^{412} , conductor 134, wiper w^{10} , contact c^{10} , (Fig. 8), conductor 301, armature r^{521} of relay R^{52} , conductor 327, relay R^{50} to battery B. This results in four 20 momentary energizations of the rotary relay R^{50} which in turn similarly energize the rotary magnet M^{20} over a circuit which may be traced from battery B through conductor 321, 322, armature r^{501} , rotary magnet M^{20} , 25 contact 324 of vertical foot-step switch 313 to ground and back to battery B. The energizations of magnet M^{20} causes the wipers of the switch S^{11} to be stepped around to the fourth row of contacts, the first step in 30 this rotary motion causing the rotary foot-step switch 314 to close its contacts.

The fourth set of impulses, six in number, coming over conductor 130 (Fig. 3), pass 35 through conductor 133, wiper w^9 , (into Fig. 8), contact c^9 , 302, r^{524} , 328, vertical relay R^{51} , 326, rotary foot-step switch 314 through battery B to ground. Each energization of the vertical relay R^{51} energizes the vertical magnet M^{21} in a circuit which may be traced 40 from battery B through circuit elements, 321, r^{511} , M^{21} to ground and back to battery B. This causes the switch S^{11} to step the wipers w^{80} — w^{40} up to the sixth pair of contacts such as c^{80} — c^{40} forming multiple 45 connections to the desired program trunk, the first vertical movement of the switch operating the vertical foot-step switch to open its contacts 324 and 325.

The single test impulse coming over conductor 135 (Fig. 3) passes through circuit elements 134 (into Fig. 8), c^{10} , 301, 327, 50 rotary relay R^{50} , 321, battery B to ground. The single momentary energization of the rotary relay opens the locking circuit of disconnect relay R^{52} which latter relay deenergizing connects the trunk conductor 301—302 through to 303—304 and to the terminals of the secondary winding of transformer 315, and completes the energizing circuit of 55 filament relay R^{53} through circuit elements B, r^{542} , R^{53} , r^{522} to ground and back to battery B.

Energization of R^{53} completes the energizing or filament circuit of the line tube 60 65 306 thus extending the connection of trunk

conductor 303—304 through transformer 315, output circuit of tube 316, conductor 305—306 forming the input circuit of tube 316, wipers w^{30} — w^{40} and contacts c^{30} — c^{40} to the desired program bus 317. After this 70 test impulse the operator's key set and circuits associated therewith become disconnected as before described leaving the calling subscriber A (Fig. 2) connected through Figs. 3 and 8 to the program bus 317 (Fig. 8) 75 over the circuit indicated in heavy lines.

When the subscriber at substation A opens the switch H^2 at the broadcast receiving set, the line is opened and the switches S^4 and S^5 are released in the same manner as that 80 previously described as resulting from the opening of the line at the telephone switch-hook H after a telephone connection. When the switch S^5 , in releasing, disengages its wiper w^{147} from contact c^{197} (Fig. 8) the 85 holding relay R^{54} is deprived of its ground connection through conductor 326, contact c^{197} , wiper w^{147} (Fig. 3) and armature r^{513} . The retraction of armature r^{542} of holding relay R^{54} opens the circuit of filament relay R^{53} to deenergize the filament of line tube 316, and closes the circuit of the release magnet M^{22} through circuit elements B, r^{542} , M^{22} , 314 to ground. Energization of release magnet M^{22} causes the switch S^{11} to 90 release and return to the normal position indicated first closing the contacts of vertical foot-step switch 313 and lastly actuating the rotary foot-step switch 314 to open its contacts which deenergizes the release magnet, 95 restoring all the circuits to the normal condition shown.

While I have here shown a simple line tube 316 connected as a stage of audio amplification, it is to be understood that this 105 simple showing is by way of example for the purpose of disclosure only and that the invention is not limited thereto but contemplates the use of a set of several tubes in place of the single tube shown which set may 110 constitute an amplifying set for either audio frequencies, radio frequencies or both, or may constitute a complete receiving set adapted to receive directly on the carrier wave frequency.

What I claim is:

1. In a system of broadcast distribution, a central station, subscribers' stations and wire lines interconnecting them, a source of electrically transmitted broadcast signaling 120 currents at the central station, a plurality of one-way amplifying units for said signaling currents, mechanically actuated switching links at the central station, circuit connections from said switching links to said amplifiers, said subscribers' lines and said source, respectively, there being one amplifier unit per line only, and means to close said circuits when a switching operation is 125 complete, so that the corresponding unit is 130

automatically brought into operative condition, in such relation to its line as to amplify in the direction of said line when calling, only.

- 5 2. In a combined telephone exchange and broadcast distribution system, a central station, subscribers' stations and wire lines interconnecting them, a source of electrically transmitted broadcast matter at the central 10 station, a line audion tube, automatic switching means having a busy test release circuit and arranged for interconnecting said subscribers' lines, and automatic switching means without a busy test release circuit for 15 connecting the output circuit of said tube with any one of said lines individually and the input circuit to said source.

3. In a system of broadcast distribution, a central station, subscribers' stations and wire 20 lines interconnecting them, a source of electrically transmitted broadcast signaling currents at the central station, one-way amplifying audion tubes at the central station, and automatic switching means for selectively 25 connecting the output circuit of one of said tubes with one of said lines individually and means for connecting the input circuits of all of said tubes when so selected with said source in common.

- 30 4. In a system of radio broadcast distribution, a telephone central station with subscribers' substations and wire lines connecting them with the central station, a plurality of radio receiving sets at the central station, a plurality of individually available one-way audion tube amplifying sets at the central station and automatic switching means, with circuit connections therefrom to one or more of said lines, to one of said amplifying sets, and to said radio receiving sets, and means controlled by a calling subscriber to actuate said switching means to close said circuits and thereby to connect his line through one of said amplifying sets to 45 one of said radio receiving sets, to amplify in the direction of the calling line only.

5. In a system of radio broadcast distribution, a telephone central station with subscribers' substations and wire lines connecting them with the central station, a plurality of radio receiving sets at the central station, link circuits terminating in automatic connector switches, automatic switching means for connecting a subscriber's line to any of 55 said link circuits, some of said link circuits containing audion tubes operatively connected therein, and multiple line terminals for said subscribers' lines, the connector switches of the links not containing audion tubes being provided with the usual busy test circuit and having access to said multiple line terminals only, and the connector switches of the links containing audion tubes being without a busy test circuit and having access 65 to said radio receiving sets only.

6. In a system of radio broadcast distribution, a telephone central station with subscribers' substations and wire lines connecting them with the central station, a plurality of radio receiving sets at the central station, link circuits terminating in automatic connector switches, automatic switching means for connecting a subscriber's line to any of said link circuits, some of said link circuits containing audion tubes operatively connected therein, means for transmitting a test impulse to each link circuit and multiple line terminals for said subscribers' lines, the connector switches of the links not containing audion tubes having access to said multiple line terminals only, and provided with means responsive to said test impulse to test the condition of a line, and the connector switches of the links containing audion tubes having access to said radio receiving sets only, and each provided with means responsive to said test impulse to energize the associated tube.

7. In a system of one-way radio broadcast distribution, a telephone central station with subscribers' substations and wire lines connecting them with the central station, automatic switching means at the central office comprising link circuits terminating in connector switches, different switches having access to different groups of subscribers' and of broadcasting terminals, those switches having access to said broadcasting terminals having audion amplifying tubes in their associated link circuits arranged to transmit and amplify in the direction of the calling subscriber only.

8. In a system of one-way radio broadcast distribution, a telephone exchange system having a central station with subscribers' substations connected therewith by wire lines and mechanically operating switching means at the central station for interconnecting the subscribers' wire lines, radio broadcast receiving means at the central station, having its output circuit arranged to be connected with any desired number of subscribers' lines in parallel through said automatic switching means without said output terminals testing busy to any subscriber, and means operable only in the connection of a subscriber's line with the said broadcasting output circuit to include an audion tube in said circuit arranged to transmit and amplify in the direction of the subscriber's line only.

9. In a system of radio broadcast distribution, a central station with subscribers' substations connected therewith through wired lines, a radio relay set at the central station, one way amplifying sets at the central station less than the number of lines, and automatic switching means for interchangeably connecting said one way amplifying sets between said subscribers' lines and said

relay set to take from said relay set in common and transmit the signals over the subscribers' lines individually.

10. In a system of broadcast distribution, 5 a central station, subscribers' stations and wire lines interconnecting them, a source of electrically transmitted broadcast signaling currents at the central station, amplifying audion tubes at the central station, automatic switching means for selectively connecting the output terminals of said tubes with said lines separately and individually and the input terminals of said tubes, with 15 said source of broadcast signaling currents in common, and busy test means associated with said amplifying tubes operable to prevent the connection of more than one line with the same audion tube.

11. In a system of broadcast distribution,

a central station, subscribers' stations and 20 wire lines leading therefrom to the central station and terminating thereat in line terminals, a source of electrically transmitted broadcast matter having distributing terminals at the central station, switching 25 means for connecting any one of said line terminals with any other of said line terminals or said distributing terminals, amplifying means, and means operable to exclude said amplifying means in the connection of 30 a line terminal with a line terminal and to include said amplifying means in the connection of a line terminal with said distributing terminals.

In testimony whereof I hereunto affix my 35 signature.

EDWARD E. CLEMENT.
